UNITED STATES PATENT OFFICE.

WILLIAM W. WARD, OF PELHAM, GEORGIA.

DESIGN FOR A MOP-HEAD.

SPECIFICATION forming part of Design No. 27,384, dated July 20, 1897.

Application filed June 8, 1897. Serial No. 639,926. Term of patent 7 years.

To all whom it may concern:

Be it known that I, WILLIAM W. WARD, a citizen of the United States, residing at Pelham, in the county of Mitchell and State of Georgia, have invented a new and original Design for a Mop-Head, of which the following is a specification.

This invention relates to a new and original design for a mop-head; and it has for its object to provide a design of this character that shall be both useful and ornamental.

The leading feature of the design resides in a flat rectangular body having longitudinally and transversely aligned rows of large circular openings, a series of smaller circular openings alternating with the rows of large circular openings, and a plurality of short cylindrical tubes lying in the plane of said large circular openings and projected from one side of the flat rectangular body, the centermost tube being disposed at an oblique angle.

A minor feature of the design resides in providing said cylindrical tubes with annular beads directly adjacent to the side of the flat body from which the tubes are projected.

In the drawings, Figure 1 is a top plan view of a mop-head embodying the herein-described design. Fig. 2 is a bottom perspective view. Fig. 3 is a bottom plan view. Fig. 4 is a central vertical cross-sectional view.

Referring to the drawings, the numeral 1 designates the flat rectangular body of the mop-head, having an undulating edge 2. The said body 1 is further provided with longitudinally and transversely aligned rows of large circular openings 3 and a series of smaller circular openings 4, alternating with the rows of large circular openings 3. From one side of the flat body 1 are projected a plurality of short cylindrical tubes 5, which lie in the plane of the large circular openings 3 and are provided with annular beads 6, directly adjacent to the side of the body from which they are projected. The centermost tube (designated by the numeral 5^a) is disposed at an oblique angle to the vertical center of the body 1.

What is claimed is—

The design for a mop-head herein shown and described.

In testimony that I claim the foregoing as my own I have hereto affixed my signature in the presence of two witnesses.

WILLIAM W. ^{his} X WARD.
